FIG. 4.

INVENTOR:

JOHN A CARR,
By: Otto de Ringer,
his attorney.

Patented Jan. 1, 1929.

UNITED STATES PATENT OFFICE.

JOHN A. CARR, OF LOS ANGELES, CALIFORNIA, ASSIGNOR TO WESTERN CONCRETE PIPE COMPANY, OF LOS ANGELES, CALIFORNIA.

WIRE-COLLAR MACHINE.

Application filed November 12, 1927. Serial No. 232,851.

This invention relates to devices used for winding and tying reinforcements to be imbedded in concrete pipes, or parts of pipes.

One of the objects of this invention is to facilitate a winding and tying of reinforcements by automatically adjustable supports.

Another object is to provide a device that can be adjusted to different diameters.

Another object is to provide a device in which the multitude of pins, around which reinforcing wire is to be wound, are firmly mounted within the device shiftable through the rim over which the reinforcement is wound.

Another object is to provide a mechanism by which the rim sections and the multitude of pins can be adjusted and shifted to accommodate reinforcing wire for various diameters and for various widths by simple movements of levers.

Other objects will appear from the following description and appended claims as well as from the accompanying drawing, in which—

Fig. 1 is a side elevation of a device with rim sections, and having a multitude of pins in connection with levers to be operated collectively or separately by main levers or handles, portions being broken away to illustrate inside connections and cooperative movements of the several parts.

Fig. 2 is a fragmentary cross section on line 2—2 of Fig. 1.

Fig. 3 is a fragmentary cross section through the rim and adjusting strips by which the pins are adjusted axially in relation to the whole device.

Fig. 4 is a fragmentary plan view of the rim.

The reinforcements for concrete pipes are first wound about a form of a size to become imbedded in the finished concrete pipe.

Since concrete pipes vary very much in length and diameter, the reinforcements, too, must vary accordingly.

A common method of providing reinforcements is by having various forms as to diameter and length with a multitude of holes into which pins are put about which the wire is wound and tied. To remove a finished reinforcement from such a form, the pins must first be withdrawn from the form before the reinforcement can be removed in an axial direction.

To facilitate a winding and accommodate

reinforcements for various sizes of pipes, this new invention provides adjustable rim sections and pins to be withdrawn radially below the outside surface of the rim, so that on a finishing of a reinforcement all the pins are 60 simply withdrawn to within the device and the rim sections are collapsed sufficiently radially towards the center to make a removal of the reinforcement easy from such a collapsed or partly collapsible form. 65

Especially is this new device suited for winding and tying reinforcements for the comparatively narrow collars for concrete pipes.

As illustrated in the drawing in Fig. 1 70 the rim sections 4 are shiftable mounted in a radial direction. Guides 5 are for this purpose provided on the central frame structure 6.

To facilitate a uniform control of several 75 rim sections, gears 7 are meshed with a central gear 8 by which the rotating movement from the central shaft 9 can be transformed into reciprocating movements upon the several rim sections by means of connecting rods 80 10. The connecting rods 10 are pivotally connected to the rim sections as indicated at 11 at one end, and also pivotally connected at the opposite end as indicated at 12 to the gear 7. The connection at 12 is eccentric to the 85 center 13 of the gears.

A lever 14 is mounted on the shaft 9 by which the rim sections 4 may be set for a certain diameter. A setting pin is for this purpose provided at a suitable point in the 90 lever 14, having a spring 16 within the handle member 17 by which the pin 15 is yieldingly held in setting position.

An arched bar 18 provided with a suitable number of perforations 19 serves to facilitate a setting of the lever 14 and thereby of the rim sections 4 to desired positions. A number of pins 20 are provided to shift through the several rim sections to project from the outside of the rim sections so that 100 reinforcing wire may be wound and tied around the pins over the outside of the rim sections.

These pins are preferably mounted on separate cross bars 20_a in groups for each of 105 the rim sections.

The cross bars 20_a are shiftable within guides 21 mounted on the central frame structure 6.

Links 22 connect to the double acting 110

levers 23 which in turn connect to a central turning plate 24 by means of connecting rods 25. Since the central plate 24 is in this manner connected to all the cross bars 20, and thereby to all the pins 20 in the several rim sections 4, a single movement by a simple lever 25 is sufficient to project the pins to the outside of the rim and on the other hand to withdraw all pins into the inside from the outside of the rim.

While adjustments for different diameters of pipes or pipe collars are taken care of by the movements of the rim sections and of the pins as far as described above, for adjusting the pins for longer or shorter pipes or for narrower collars, guide bars 26 are provided on the rim sections for adjustments in an axial direction. The guide bars can be adjusted by means of the bolts 27, the rim sections having for this purpose slots 28 in which the bolts can be shifted back and forth axially in relation to the whole structure. Other slots 29 serve to allow the pins to project through the rim sections 4 in the various adjusted positions. Sleeves 30 serve to guide the pins and to prevent a dropping of the pins from the rim sections when the pins are drawn to their innermost positions.

The sleeves 30 are provided with enlarged ends 31 seating in countersunk holes in the plates 26. The sleeves are hereby held with their enlarged ends between the rim portions 4 and the guide bars 26, and, by making the countersunk holes large enough, the sleeves 30 may yield suitably so that the pins 20 may easily shift through the sleeves in and for the different adjusted positions.

With this structure the rim sections are adjusted to a desirable diameter between gears 7 and 8 and the lever 14.

The said pin 15 is adjusted to one of the holes 19 in the segment bar 18 so that the rim sections can thereby be held firmly in adjusted position. The multitude of pins 20 are then merely shifted through the rim sections by a simple movement of the lever 25, thereby making the whole structure ready to receive reinforcement wire over the outside of the rim sections to be tied and wound around the pin ends 20.

As soon as a reinforcement is finished, the pins are withdrawn into the inside by another simple movement of the lever 25, and the tension of the reinforcement may be suitably released by an inward movement of the rim sections from the adjusted position, so that the finished reinforcement can easily be removed from the smooth pinless outside of the structure.

The rim sections and pins are then again set back to the previous adjusted position and one after another reinforcement can be wound in the manner set forth above.

From the illustration in Fig. 4 it will be clear that wire or reinforcing material can

be wound around the whole drum and cross-wise between the pin ends 20 protruding through the drum. The reinforcing material can be wound in any desired and customary manner and, after having been wound, can be removed from the drum or rim by withdrawing the pins to positions within the contours of the rim and further contracting the rim sections to a smaller diameter, as described above.

Having thus described my invention, I claim:

1. In a reinforcement winding machine, a rotatably mounted sectioned drum embodying means by which the sections of the drum are adjusted to different diameters, and pins mounted to project through the drum and embodying shifting means adapted to allow a withdrawing of the pins inwardly into disappearing position within the outer contours of the sectioned drum.

2. In a reinforcement winding machine, a sectioned drum embodying means by which the sections of the drum can be adjusted to different diameters, the drum having apertures, and pins mounted in the drum and embodying shifting means to shift the pins outwardly through said apertures.

3. In a reinforcement winding machine, a sectioned drum having apertures, pins mounted in the drum to shift through the apertures about which reinforcement may be wound over the drum, and controlling means for setting the sections of the drum for different diameters.

4. In a reinforcement winding machine, a sectioned drum having apertures, pins mounted in the drum to shift through the apertures about which reinforcement may be wound over the drum, controlling means for setting the sections of the drum for different diameters, and other controlling means for the pins to project the pins through the drum and adapted to withdraw the pins to within the contours of the drum.

5. In a reinforcement winding machine, a sectioned drum having apertures, pins mounted in the drum to shift through the apertures about which reinforcement may be wound over the drum, controlling means for setting the sections of the drum for different diameters, and other controlling means for the pins to project the pins through the drum and adapted to withdraw the pins to within the contours of the drum for the different adjusted diameters of the sectioned drum.

6. In a reinforcement winding machine, a sectioned drum having apertures, pins mounted in the drum to shift through the apertures about which reinforcement may be wound over the drum, controlling means for setting the sections of the drum for different diameters, and adjusting means for setting the pins to move through the drum

in different positions axially so as to allow a winding of wider and narrower reinforcements over the drum around the differently set and adjusted protruding pin ends.

5 7. In a reinforcement winding machine, a sectioned drum having apertures, pins mounted in the drum to shift through the apertures about which reinforcement may be wound over the drum, controlling means 10 for setting the sections of the drum for different diameters, adjusting means for setting the pins to move through the drum in

different positions axially so as to allow a winding of wider and narrower reinforcements over the drum around the differently set and adjusted protruding pin ends, and guides for the pins by which the pins receive a comparatively long support for the different adjusted diameters of the drum in relation to the longitudinal axes of the pins.

15 20 In testimony that I claim the foregoing as my invention I have signed my name.

JOHN A. CARR.
